(57) **CLAIM**

We claim the ornamental design for a wheelie bar assembly for a model vehicle, as shown and described.

DESCRIPTION

FIG. 1 is a front elevation view of a wheelie bar assembly for a model vehicle;

FIG. 2 is a rear elevation view thereof;

FIG. 3 is a top plan view thereof;

FIG. 4 is a bottom plan view thereof;

FIG. 5 is a right side elevation view thereof, the left side elevation view being a mirror image thereof;

FIG. 6 is a top, front, and left side perspective view thereof; and

FIG. 7 is a top, rear, and right side perspective view thereof, when installed on the rear of an exemplary model vehicle. The broken line showing portions of the wheelie bar assembly and environmental structure of a model vehicle do not form part of the claimed design.
